UNITED STATES PATENT OFFICE.

WILLIAM WOODWARD ROSENFIELD, OF NEW YORK, N. Y., ASSIGNOR TO ROSENFIELD
MANUFACTURING COMPANY, A CORPORATION OF NEW YORK.

COIN-OPERATED MACHINE.

939,746.

Specification of Letters Patent.

Patented Nov. 9, 1909.

Application filed May 21, 1902. Serial No. 103,807.

To all whom it may concern:

Be it known that I, WILLIAM WOODWARD ROSENFIELD, a citizen of the United States, residing at New York city, county of New York, and State of New York, have invented certain new and useful Improvements in Coin-Operated Machines, fully described and represented in the following specification and the accompanying drawings, forming a part of the same.

This invention relates to coin operated machines or devices, and the invention aims generally to improve the construction of machines of this class and especially to provide a machine of such construction as to effectually guard against its being operated with the use of an improper article, such as a coin or disk of any other size or material than that of a genuine coin of the denomination by which the machine is intended to be operated.

A full understanding of the invention can best be given by a detailed description of a construction embodying the various features of the invention in their preferred form, and such a description will now be given in connection with the accompanying drawings showing a vending machine constructed in accordance with the invention.

In said drawings:—Figure 1 is a section taken on line 1 of Fig. 2, showing the operating mechanism of the machine in elevation and with the casing partly broken away. Fig. 2 is a section on line 2 of Fig. 35 1, the casing in this figure also being broken away. Fig. 3 is a section on line 3 of Fig. 2. Fig. 4 is a section similar to Fig. 3, but showing the operating parts in a different position. Fig. 5 is a section on line 5 of Fig. 4. Fig. 6 is a section on line 6 of Fig. 4. Fig. 7 is a sectional view similar to Fig. 3 showing a preferred duplex stop attachment. Fig. 8 is a section on line 8 of Fig. 7. Fig. 9 is a section similar to Fig. 8 but showing the parts in another position. Fig. 10 is a detail.

Referring to the drawings, A represents the casing of the machine, in the upper rear portion of which there is arranged a vertical storage chute B for holding the articles to be sold. Just below its bottom b, the chute is formed with a rear opening b' for the delivery of the articles one by one therefrom. The articles are delivered by means of a slide 10, which passes through an opening b

in the front side of the chute opposite the opening b', and by which the bottom article in the chute is shoved outward through the delivery opening b'. Beneath the delivery opening b' there is arranged a delivery chute 60 C, by which the articles as they drop from the chute B are guided to a position near the front of the machine convenient to be reached by the purchaser.

The operating parts are mounted mostly 65 within a protecting casing 11. The slide 10 is mounted in a suitable guideway 12 extending within the casing 11 and outward beyond the casing, and is formed with a coin receiving slot 13, which, in the normal or 70 outward position of the slide is outside of the casing 11, so as to permit a coin to be introduced therein. The slide is normally held in its outward position by means of a spring 14, and is provided with a knob 15 75 by means of which, after the coin has been introduced into the slot 13, the slide is pushed inward so as to cause the delivery of the bottom article from the chute B.

If the slide is pushed inward without the 80 proper coin having been first placed in the slot 13, its inward movement will be limited by means of a stop 16 which engages a lug 17 on the under side of the slide near its forward end and thereby stops its movement 85 before it has advanced far enough to shove the article from the chute. The stop 16 is carried by a pivoted lever 19, to which it is connected by means of arms 18 extending on either side of the path of the slide. The 90 lever 19 is pivoted at 20 and is normally held in position to maintain the stop 16 in the path of the lug 17 by means of a spring 21 which acts on a stud 2 carried by the lever to hold said stud against a stop 3, 95 which is preferably adjustable, as shown. The other arm of the lever 19 has a sharpened end or portion preferably in form of a knife edge 22 preferably extending transversely of the lever and transversely of the 100 line of movement of the coin, and in position to engage the edge of the coin as the latter is moved inward by the slide, and the parts are proportioned and located so that as a coin of the proper size is carried inward by the slide, the edge of the coin will engage the knife edge 22 and move the lever 19 against the tension of the spring 21 sufficiently to carry the stop 16 downward out of the path of the lug 17, thus permitting 110

the slide to be pushed inward the full distance necessary to deliver an article from the chute B. The two arms of the lever 19 are so proportioned, the arm carrying the stop being comparatively long and the arm carrying the knife edge comparatively short, and the spring 21 is of sufficient strength, so that considerable pressure is necessary to be exerted on the knife edge 22 in order to cause the required movement of the lever. This being so, it is evident that if a disk of comparatively soft material, such as lead or wood, be used in place of a coin, even though of proper size, the knife edge 22 will sink 15 into the disk and the lever 19 will not be given its required movement and the stop 16 will remain in position to engage the lug 17 and limit the inward movement of the slide. The knife edge or other sharpened member 20 is preferably adjustably secured to the arm of the lever 19 so that it may be adjusted vertically, as by means of a screw 24, to secure the proper projection of the knife edge into the path of the coin and the desired 25 throw of the lever. The knife edge or other sharpened member should not be so sharp as to bite into the edge of a proper coin and so prevent the movement of the stop out of the path of the lug 17 when a proper 30 coin is in place in the slide.

In order to lessen the resistance to the inward movement of the slide which would otherwise occur when the coin comes in contact with the knife edge, an anti-friction 35 roll 25 is mounted in an opening in the slot or groove 26 which extends beneath the path of the coin slot 13 and into which the coin extends and by the bottom of which it is supported as it is being carried inward by the slide. This anti-friction roll is positioned directly below the knife edge 22 so that at the time the upper edge of the coin is in engagement with the knife edge, the lower edge of the coin will be supported by the roll. 40 The roll 25 is also preferably formed with a circumferential groove 27 located centrally of the path of the coin and of a width slightly less than the thickness of a coin such as the machine is intended to be operated by. 45 With the roll so formed, if a coin or other disk of less than the proper thickness be used, the edge of the coin will enter the groove 27 and the coin will thus drop sufficiently to prevent its causing the necessary 50 movement of the lever 19 for permitting the full inward movement of the slide. By having the groove 27 formed in the periphery of the roll 25, long wearing edges are provided, different portions of which are successively brought into operative position by the rotation of the roll, thus insuring a longer life for this part of the machine than if the groove 27 were formed in a stationary part. I do not wish to be limited, 55 however, in this feature of providing an

opening to receive an edge of the coin at the time the coin is passing the knife edge, to the use of the anti-friction roll 25; and while the opening is preferably provided in the part which supports the coin against the pressure of the knife edge, it might evidently be provided in the knife edge.

The coin supporting groove 26 ends just beyond the roll so that by the time the slide reaches the end of its movement the coin 75 will be free to fall from the slot 13. A suitable coin receptacle as 30 is provided. To insure the falling of the coin from the slide after it has done its work, an ejector 31 is provided which as the slide nears the end 80 of its inward movement engages the upper edge of the coin to force it downward.

In order to prevent the coin from being withdrawn by the outward movement of the slide after it has been carried inward a certain distance, a spring stop 35 may be provided which normally extends across the path of the coin above the slide and is formed with a beveled face, as shown in dotted lines in Fig. 2, so that on the inward 90 movement of the coin the stop will be engaged by the coin and pushed out of the path of the coin. When the coin has been moved past the stop, the stop will snap back into normal position and prevent the withdrawal of the slide until the coin has been discharged therefrom into the coin receptacle. 95

A spring stop 40 is preferably provided as an additional means for limiting the inward 100 movement of the slide when no coin has been inserted in the slot 13, or when a coin or disk of less than the proper thickness, or a disk or washer having a central perforation, has been inserted in the slot. This 105 stop 40 preferably extends into a rabbet 41 cut in the face of the slide with its vertical side in the same plane with the nearest side of the coin slot 13 and extending the necessary distance forward and rearward of the 110 slot 13. The stop 40 is mounted so as to extend into this rabbet and bear against the vertical side thereof so that, when the slide is pushed inward without any coin in the slot 13 or with one of less than the proper 115 thickness, the stop, when the slot 13 comes opposite it, will enter the slot and by engaging the rear side thereof prevent further inward movement of the slide. When, however, a coin of the proper thickness is 120 in the slot 13, the stop will thereby be held from entering the slot and will not act to limit the inward movement of the slide. The rear face of the stop 40 is beveled so that it will not act to interfere with the 125 return movement of the slide.

In place of the stop 35 for preventing return movement of the slide until after it has been given its complete inward movement, and as an additional means for insur- 130

ing against inward movement of the slide when no coin has been inserted in the slot 13, I preferably provide a duplex stop 50, as shown in Figs. 7, 8 and 9. This stop as shown has a stud or finger 51, and is under yielding tension, as by means of a spring 52, to carry the finger 51 into position to engage an abutment 53 on the slide and thus limit the inward movement of the slide. There are preferably a plurality of the abutments 53 formed by a series of notches in the edge of the slide as shown. The stop normally extends into the path of the coin as the latter moves with the slide, and is so formed and mounted, being preferably pivoted, as shown, that when the slide is moved inward with a coin in the slot 13, the coin will force the stop out of its path and the finger 51 will be prevented from engaging the abutments 53, and the slide will thus be permitted to make its full inward movement. The stop is provided with a shoulder 54 such that when the slide has been moved inward so far as to carry the outer edge of the coin past the shoulder the stop will move slightly under the influence of its spring to project the shoulder behind the coin. The stop will thus act to prevent return movement of the slide after it has been moved a certain distance inward and until the coin has been discharged. The stop preferably has a plurality of the shoulders 54 formed by a succession of notches as shown, so that as the slide is moved inward the shoulders will move successively into position to prevent return movement of the slide. The stop 50 thus acts to limit the inward movement of the slide when there is no coin in the slot, and to prevent return movement of the slide when there is a coin in the slot and thus insure against the coin being abstracted from the slide by the slide being moved outward before the coin has been properly discharged therefrom. By providing the slide with a plurality of the abutments 53, all possibility of the slide being drawn only part way out after the discharge of the coin and then pushed in again is avoided. The coin having been discharged, the slide must be drawn all the way out and another coin inserted before it can be pushed in again.

Fig. 10 shows a modified construction for providing an adjustable sharpened member on the lever 19. As here shown, the sharpened member 22 is secured to and carried by the adjusting screw 24 which passes through the lever 19.

The operation of the machine will be understood from the foregoing description. It will be understood that the invention or parts thereof as claimed may be applied to any coin operated or actuated machine for which it may be found applicable, and that I am not to be limited to the particular

form of mechanism shown for the purpose of illustrating the invention and to which the foregoing description has been mainly confined, but that the invention includes other forms, combinations and arrangements of devices within the claims. It will be understood also that by the term "coin operated machine" as used in the claims I intend to include all coin or check operated or actuated machines or parts of machines to which the invention may be applicable whether used as parts of vending machines or otherwise.

What I claim is:

1. In a coin operated machine, the combination of a movable coin receiving member for advancing the coin edgewise, means for limiting the movement of said member, a knife edge extending transversely of the direction of movement of the coin receiving member and held under yielding tension in position to engage the edge of the coin as the latter is advanced by the coin receiving member, and connections between the knife edge and said means for controlling said means to permit the coin receiving member to make its full movement, substantially as described.

2. In a coin operated machine, the combination of a movable coin receiving member for advancing the coin edgewise on edge, means for limiting the movement of said member, a knife edge extending transversely of the direction of movement of the coin receiving member and held under yielding tension in position to engage the edge of the coin as the latter is advanced by the coin receiving member, and means between the knife edge and said means for controlling said means to permit the coin receiving member to make its full movement, substantially as described.

3. In a coin operated machine, the combination of a movable coin receiving member for advancing the coin edgewise, a stop for limiting the movement of said member, a knife edge extending transversely of the direction of movement of the coin receiving member and held under yielding tension in position to engage the edge of the coin as the latter is advanced by the coin receiving member, connections between the knife edge and said stop for causing said stop to be moved to permit the coin receiving member to make its full movement, and means for preventing return movement of the coin receiving member by engagement with the coin after the coin receiving member has been moved a distance greater than that to which it is limited by said stop, substantially as described.

4. In a coin operated machine, the combination of a movable coin receiving member, means for limiting the movement of said member, a sharpened member held under yielding tension in position to engage the

edge of the coin as the latter is advanced by the coin receiving member, connections between the sharpened member and said means for controlling said means to permit 5 the coin receiving member to make its full movement, and a duplex stop having a part for preventing return movement of the coin receiving member by engagement with the coin and having a part for engaging the 10 coin receiving member to limit its operative movement when no coin is in position thereon, substantially as described.

5. In a coin operated machine, the combination with a movable coin receiving member, of a duplex stop for limiting the operative movement of the coin receiving member and preventing return movement thereof, said stop having a part projecting into the path of the coin to cause the stop to be 15 moved by the coin to permit the coin receiving member to make its full operative movement and having a part for preventing return movement of the coin receiving member, substantially as described.

25 6. In a coin operated machine, the combination with a movable coin receiving member, of a spring pressed duplex stop for limiting the operative movement of the coin receiving member said stop having a part 30 projecting into the path of the coin to cause the stop to be moved by the coin to permit the coin receiving member to make its full operative movement, and having a plurality of coin engaging shoulders for preventing 35 return movement of the coin receiving member until the coin has been discharged, substantially as described.

7. In a coin operated machine, the combination with a movable coin receiving member having a plurality of abutments, of a duplex stop for engaging said abutments to limit the operative movement of the coin receiving member said stop having a part 40 projecting into the path of the coin to cause the stop to be moved by the coin to permit the coin receiving member to make its full operative movement, and having a coin engaging part for preventing return movement of the coin receiving member until the 45 coin has been discharged therefrom, substantially as described.

8. In a coin operated machine, the combination with a movable coin receiving member having a plurality of abutments of a duplex stop for engaging said abutments to limit the operative movement of the coin receiving member said stop having a part 50 projecting into the path of the coin to cause the stop to be moved by the coin to permit the coin receiving member to make its full operative movement, and having a plurality of coin engaging shoulders for preventing 55 return movement of the coin receiving member until the coin has been discharged therefrom, substantially as described.

9. The combination of the coin receiving slide 10 having a plurality of abutments 53, and the spring pressed duplex stop 50 for engaging said abutments and having a part normally extending into the path of the coin 70 formed with a plurality of shoulders 54, substantially as described.

10. The combination of the coin receiving slide 10 for advancing the coin edgewise, lever 19, stop 16 carried by the lever 19, 75 knife edge 22 carried by the lever 19 and extending transversely of the direction of movement of the slide 10, and in position to engage the edge of the coin carried by the slide and coin ejector 31, substantially as 80 described.

11. In a coin operated machine, the combination of a coin receiving member for advancing the coin edgewise, a stop for limiting the movement of said member, a lever 85 inovable against yielding tension for moving the stop to permit said member to make its full movement, a knife edge carried by said lever in position to engage the edge of the coin as the latter is advanced by the slide 90 and extending transversely of the direction of movement of the coin receiving member, and means for adjusting the sharpened member on the lever to cause it to extend more or less into the path of the coin, substantially as described.

12. In a coin operated machine, the combination with a movable coin receiving member, of a duplex stop for limiting the operative movement of the coin receiving 100 member and preventing return movement thereof, said stop being formed to be engaged by the coin and thereby held in position to permit the coin receiving member to make its full operative movement and having a part for preventing return movement of the coin receiving member, substantially as described.

13. In a coin operated machine, the combination with a movable coin receiving 110 member having an abutment, of a duplex stop for engaging said abutment to limit the operative movement of the coin receiving member, said stop being formed to be engaged by the coin and thereby held in position to prevent it from engaging said abutment and to permit the coin receiving member to make its full operative movement, and having a coin engaging part for preventing 115 return movement of the coin receiving member until the coin has been discharged therefrom, substantially as described.

14. In a coin operated machine, the combination, of a movable coin receiving member, a stop for limiting the movement of 125 said member, a lever by which said stop is carried, and a coin engaging part carried by said lever close to its fulcrum and adapted to be engaged by the edge of the coin to cause the lever and stop to be moved to per- 130

mit the coin receiving member to make its full movement, said part being adjustable on the lever to extend more or less into the path of the coin.

5 15. In a coin operated machine, the combination, of a movable coin receiving member, a stop for limiting the movement of said member, a lever for moving the stop to permit said member to make its full movement, a part carried by said lever in position to be engaged by the edge of the coin and to be moved thereby to cause the lever and the stop to be moved to permit the coin receiving member to make its full movement, said 10 part being adjustable on the lever to cause it to extend more or less into the path of the coin.

15 16. In a coin operated machine, the combination, of a movable coin receiving member, a stop for limiting the movement of said member, a lever by which said stop is carried, and a coin engaging part carried by said lever close to its fulcrum and adapted to be engaged by the coin to cause the 20 lever and stop to be moved to permit the 25

coin receiving member to make its full movement, said part being adjustable on the lever to extend more or less into the path of the coin.

17. In a coin operated machine, the combination, of a movable coin receiving member, a stop for limiting the movement of said member, a lever for moving the stop to permit said member to make its full movement, a part carried by said lever in position to be engaged by the coin and to be moved thereby to cause the lever and the stop to be moved to permit the coin receiving member to make its full movement, said part being adjustable on the lever to cause it to extend more or less into the path of the coin. 30 35 40

In testimony whereof, I have hereunto set my hand, in the presence of two subscribing witnesses.

WILLIAM WOODWARD ROSENFIELD.
